Patented Oct. 3, 1922.

UNITED STATES PATENT OFFICE.

BERNARD P. JOHNSON AND RALPH SCHROEDER, OF CINCINNATI, OHIO.

TOY.

Application filed June 20, 1921. Serial No. 478,905.

To all whom it may concern:

Be it known that we, BERNARD P. JOHNSON and RALPH SCHROEDER, citizens of the United States, residing in Cincinnati, in the county of Hamilton and State of Ohio, have invented new and useful Improvements in a Toy, of which the following is a specification.

This invention relates to a toy designed for use in connection with the operation of phonographs and is particularly of the nature of a marionette or puppet, being actuated by the rotative action of the record turntable.

15 An object of our invention is to produce a toy of the class above described, in which the various parts of the image are given peculiarly characteristic movements to produce the effect of a marionette dancing.

20 A further object is to produce a toy of the class described in which the dancing or other movements may be timed in accordance with the time of the piece being played from a record located on the turntable of

25 the phonograph.

These and other objects are attained in the toy described in the following specification and illustrated in the accompanying drawing in which—

30 Fig. 1 is an elevational view, somewhat in diagrammatic form of a toy embodying our invention, mounted on a turntable which, for purposes of purely diagrammatic illustration is shown considerably smaller relatively to the marionette, than is actually the case.

Fig. 2 is a fragmental perspective view of the timing mechanism by means of which the marionette is caused to dance in synchronism with the time of the piece being played.

In the construction of our improved toy we provide an upright 3 which is secured to a transversely extending arm 4 which projects across the record 5 on the turntable 6 and is supported by a foot 7 which rests upon the wood top of the phonograph case adjacent to the turntable. Upright 3 carries a member 8 which is shaped to represent the chest or bust of the marionette. To the lower end of this is pivotally attached, at a point 9, the hip portion 10 of the torso. At the sides of the member 8, the upper portions 11 and 12 of the arms are pivotally

attached at points 13 and 14. To these arm portions the forearm portions 15 and 16 are attached at points 17 and 18. At the upper part of the member 8 a head and neck member 19 is attached pivotally as at point 20. The hands of the forearm elements 15 and 16 are attached to the head and hip members 19 and 10 respectively at points 21 and 22 if desired, in order to simulate more closely the movements of a dancer. To the lower portion of hip member 10, thigh elements 23 and 24 are pivotally attached at points 25 and 26, and to the lower ends of thigh elements 23 and 24 are pivotally attached at points 27 and 28 the combined lower limb and foot elements 29 and 30. Head and neck member 19 is provided with an extension 31 to which a link 32 is attached at a point 33, the lower end of link 32 being connected to the hip portion at point 25. Rotatively mounted in a bearing 34 is a roller 35 which carries a friction tire 36 for engagement and operation with the surface of the record 5 on the turntable. Connected at a point 37 with point 26 is a link 38 by means of which the toy is operated when roller 35 is rotated. Pivitally but frictionally secured at a point 39 on arm 4 is a finger, 40 for engaging the record centering pin 41 of the turntable, this finger, when adjusted properly, serving to space 45 roller 35 the proper distance from the center pin to time the number of rotations of the roller so that the marionette will dance in proper synchronism with the piece being played. The movements of the marionette, 50 from the drawing and description given above, being so readily understood, it is deemed unnecessary to amplify this description with a detailed description of the operation.

Having thus described our invention what we claim is—

A toy for application to phonographs, consisting of a vertical support, means adapted to retain the support any desired 100 distance from the center to the edge of the phonograph turntable, a roller rotatively mounted at the lower end of the support for engagement with the surface of a record on the phonograph turntable, the upper portion of a marionette torso rigidly attached to the upper end of the support, a torso hip portion pivotally attached at its upper

end to the upper portion of the torso, pivoted leg portions pivotally attached to the hip portion, pivoted arm portions pivotally attached to the upper portion, a head pivotally attached to the upper portion a link operatively connected with the roller and the pivot of one leg with the hip portion, and a link pivotally connecting the other leg with the head, one arm having pivotal con-

nexion with the head and the other with the hip.

In witness whereof, we affix our signatures in the presence of two witnesses.

BERNARD P. JOHNSON.

RALPH SCHROEDER.
